EDWARD E. CLEMENT, OF WASHINGTON, DISTRICT OF COLUMBIA, ASSIGNOR, BY
MESNE ASSIGNMENTS, TO FREDERICK C. STEVENS, OF ATTICA, NEW YORK.

TELEPHONE-EXCHANGE SYSTEM.

1,109,511.

Specification of Letters Patent.

Patented Sept. 1, 1914.

Application filed July 14, 1906, Serial No. 326,253. Renewed July 20, 1914. Serial No. 852,087.

To all whom it may concern:

Be it known that I, EDWARD E. CLEMENT, a citizen of the United States, residing at Washington, in the District of Columbia, have invented certain new and useful Improvements in Telephone-Exchange Systems, of which the following is a specification, reference being had therein to the accompanying drawing.

10 My invention relates to telephone exchange systems and has for its object the improvement of automatic systems by the substitution of relays for step by step switches.

15 The system which I shall hereinafter specifically describe is a full automatic system, that is, one in which the control of the relays is effected from the subscriber's station, but the general arrangement may also be 20 applied to semi-automatic systems, in which the work of setting up the switches or relays is done by an operator at the central office.

It will be observed after study of the accompanying drawings that no change will 25 be required in the mechanism or circuits in order to make the system semi-automatic, since I use only two wires and no ground for a subscriber's line, and have a perfectly clean metallic talking circuit throughout.

30 Briefly stated, my invention comprises means at a subscriber's station of making and breaking his metallic line circuit, means associated with his line at the central office to translate these makes and breaks into current 35 impulses on one side or the other of a switch or relay circuit, whereby the line may be connected to other lines. I terminate the line extension preferably in a set of relays, but I need not identify any special relay set 40 in any particular line, since any two lines having terminals in the same set of relays may be connected together by energizing the proper relays simultaneously. Taking the decimal or double digit system, suppose we 45 have two lines numbered 97, and 64, respectively, which it is desired to connect together. This may be effected by pulling down the number 90 relay, the number 60 relay, the number 7 units relay, and 50 the number 4 units relay, all at the same time. In order to simplify my description, however, I have shown the incoming calling line provided with a complete set of relays whereby it can reach any other line. 55 To call line number 97, for example, the

subscriber would send nine impulses followed by seven impulses. These nine impulses I cause to step up nine selecting relays successively, the ninth one of which closes the circuit of the number 90 tens relay of the connector group; by means of the central office line relay then, I send a single impulse which changes the selector relays and gives them control of the units relays of the connector set. They then step up in response to the seven impulses until they have picked out the number 7 units relay, and the combination of 90 and 7 gives the desired connection.

The feature of having step by step selection through relays for effecting connections between circuits, I believe is novel and original with me in a telephone system. I shall claim the same broadly, and in so doing shall use the word relay in its correct technical sense, that is to say as an agency in which contact points in one circuit are directly controlled by an electromagnet or its equivalent in another.

My invention is illustrated in the accompanying drawings wherein—

Figure 1 shows a subscriber's station with line wires terminating in the central office apparatus. Fig. 2 shows a portion of the trunk with a set of step by step relays. Fig. 3 shows a set of connector relays controlled by step by step relays in Fig. 2.

Referring now to Fig. 1, the subscriber's station comprises the usual apparatus consisting of the transmitter, receiver, ringers, condenser and switch-hook. In addition to the foregoing, I have added a simple make and break device for sending impulses to the central office. This device is represented diagrammatically by the push button P having the normally closed contacts p and p' . When the push button is depressed, the contact springs p and p' are broken, thus opening the line as the telephone is connected to the line through these contacts. At the central office the relays D and D' are bridged across the conductors 5 and 6, the relay D being connected to the grounded side of battery, while the relay D' is connected to the free side of battery. These two relays besides furnishing talking current to the calling subscriber also control the two solenoids or slow-acting relays X and X', and the joint action of the relays D and D' and these solenoids control the relays in the set

W, Fig. 2, and these in turn control or select the relays in Fig. 3. The solenoids X and X' are quick acting when energized, but after they are energized, their cores drop 5 down slowly and operate their respective contact springs. In place of these solenoids I may substitute a slow-acting relay which can be made sluggish either by mechanical means or by slipping a copper sleeve over 10 the core. The relays D and D' become energized when the subscriber removes his receiver. The relay D closing the contacts d³ and d⁴, completes the circuit of the solenoid X, which thereupon becoming energized 15 draws up its core, closing the contacts x and x' and placing battery on the contact d. The solenoids X and X' while responding to quick makes and breaks of the contacts in the relay D, do not allow their cores to 20 drop down during these makes and breaks. It follows, of course, that any makes and breaks at the subscriber's station caused by manipulating the push button P while affecting the relays D and D', only cause the 25 solenoids to remain energized with their cores drawn up. The solenoid X' has its circuit closed during these makes and breaks on account of battery being placed on the contact d by the solenoid X. During the 30 entire conversation and while impulses are being transmitted, the solenoid X remains energized while the solenoid X' only remains energized, while the impulses are being transmitted. At the end of a set of 35 impulses when the relay D is energized, the circuit of the solenoid X' is open and, becoming deenergized, its core drops down and momentarily closes the contacts x² and x³ thereby placing a grounded impulse on 40 the wire 50 which leads to the relay E', Fig. 2. The operating impulses are transmitted or repeated over the wire 20 to the relay E by the making and breaking of the contacts d and d'. The relays E² and E³ 45 attached to the trunk wires 7 and 8 and separated by the condensers C and C' from the answering end of the trunk furnish battery to the called subscriber and control the ringing relay Y.

50 Referring now to Fig. 2, the two relays E and E' which respond to the operating impulses and the switching impulses, respectively, directly control the relays F, F' and the relays of the set W. The operation 55 of the relay E closes the circuit of the relay F' which supplies battery to the contact e' of the relay E. The making and breaking of the contacts e, e' and e² operate the relays of the set W in step by step order. The 60 first impulse coming in energizes the relay E, but while this relay is in an energized condition, none of the relays in the set W are affected, but after the impulse has passed, the circuit of the relay H' is closed 65 through the contacts e' and e² as battery has

been placed on contact e' by the energizing of the relay F'. The operating of the relay H' closes the circuit of the relay W' through the contacts h and h'. Now, when the second impulse comes in and the relay E 70 is in an energized condition, the circuit of the relay W' is closed through the contacts e and e'. After the impulse has passed, the circuit of the relay H' is closed through the contacts w' and w² of the relay W'. This 75 operation can be kept up until all the relays in the set have been operated. The relays H in the lower row are simply the guard 80 relays and are operated when the relay E is deenergized and place the relays W' and W², etc., in position to be operated when the relay E is energized.

Taking Figs. 2 and 3 together, the relay W' when energized, closes the circuit of the first tens relay T'. The relay W² when energized 85 closes the circuit of the second tens relay T² while the relays W³, W⁴ and W⁵ control the relays T³, T⁴ and T⁵, respectively. The relays T', T², etc., in the upper row are the tens relays and each contains the multiples of ten lines. For a 100 line system 90 there would be ten of these relays. The drawing only shows five of these relays, the remainder being similarly arranged and their operation being identical. I have 95 shown the relays in this manner for simplicity as additional wiring would be confusing. The lower set of relays T¹¹, T¹², etc., are the units relays and each contains 100 multiples of the contacts of the upper set or tens relays. The relay T¹¹, being the first units relay, contains the multiples of the first pair of contacts in each of the tens relays T', T², etc., while the relay T¹² contains the multiples of the second pair of 105 contacts of the tens relays. The trunk wires 7 and 8 are also multiplied to contacts in the lower set or units relays. If the first tens relay T' and the first units relay T¹¹ are energized, the trunk wires 7 and 8 would 110 be connected to line 11 through the contacts t¹¹ and the first pair of contacts t', and if the third tens relay T³ and the second units relay T¹² were energized, the trunk wires 115 would be connected to line No. 32 through the contacts t¹² and the second pair of contacts t³. The tens relays are the first set of 120 relays to be operated by the relay set W and are provided with two windings, an actuating winding which is controlled by the relay F and also a locking winding which is controlled by the same relay. The locking winding of the relay is connected to the common wire 16 leading to the contacts f⁵ in the relay F, while the actuating windings are connected 125 to the common wire 15 leading to ground through the contacts f⁴ and f³ of the relay F. Individual actuating wires 23, 24, 25, 26 and 27 lead to the normally open contacts of the relays W', W², etc. The units relays 130

are only provided with a single winding and are operated after the tens set in their proper order. The winding from the first units relay T^{11} is connected in multiple with the actuating winding of the relay T' to the wire 23. The winding of the relay T^{12} is connected to the wire 24 in multiple with the actuating winding of the relay T^2 , while the relays T^{13} , T^{14} and T^{15} are connected to the 5 multiple respectively to the actuating windings of the relays T^3 , T^4 and T^5 . The other terminal of each of the units relays is connected to the common wire 14 leading to the normally open contact f^2 of the relay F .
 10 From the foregoing description it will be seen that if battery is placed on wire 23 by the relay W' , the relay T' will be operated, being connected to ground through the contacts of the relay F , but the relay T^{11} will not be affected as the common wire 14 is disconnected from ground. The relay F is in reality the switching relay and is operated after the first set of impulses by the grounded impulse being sent over the wire 20 15 by the solenoid X' . This impulse directly affects the relay E' which in turn closes the circuit of the relay F which remains locked through the contacts f and f' and under the control of the solenoid X . The operation of the relay F removes ground from the common wire 15 of the tens set of relays and connects ground to the common wire 14 of the units set of relays. This relay also by closing the contacts f^5 and f^6 places battery 20 on the locking wire 16 which thereupon keeps the tens relay which was last operated in an energized condition. When the grounded impulse is sent over the wire 20 operating the relay E' , the contacts e^8 and e^9 are broken, releasing the relay F' which thereupon removes battery from the common wire 13 leading to the locking contacts of the relays in the set W . The relays of the set W are thus restored to their normal 25 position and ready to be operated a second time to select or pick out the proper units relay. The operation of the relays W the second time is the same as already described the only difference being that after the second set of impulses the relays are not released, for the grounded impulse coming in after the second set of impulses fails to operate the relay E' as it is disconnected from battery at this time on account of the relay F being energized and breaking the contacts f^6 and f^{11} . These relays of the set W remaining energized after the second set of impulses enable me to use a single winding on the units relays as battery remains on the particular individual wire leading to the selected units relay. After the second set of impulses, the trunk is connected through to the desired line and the relay Y , Fig. 1, becomes energized in series with the 30 interrupting machine which is common to a

contact in each of the units relays. The relay Y connects generator to the called line and at the same time opens the answering end of the trunk. When the called subscriber answers the relay E^2 becomes energized and disconnects the ringing relay Y . At the end of the conversation the calling subscriber hanging up his receiver deenergizes the relays D and D' allowing the solenoid X to drop its core thereby removing battery from the holding wire 9 thereby releasing all the relays, and the apparatus is restored to its normal condition.
 35

The operation of my system is as follows:
 The subscriber at station A removing his receiver closes the circuit of the relays D and D' . The relay D closes the circuit of the solenoid X by the following path: battery B, 63, d^4 , d^5 , 54, X to ground. This solenoid in turn places battery on the contact d by the closing of the contacts α and α' . The subscriber now proceeds to set up the sending device which thereupon makes and breaks the contacts p and p' a number of times corresponding to the number desired. Suppose the number to be sent was 32. The subscriber would first set up the device to No. 3 which upon running down makes and breaks the contacts p and p' . These makes and breaks operate the relays D and D' a number of times corresponding to the number to be sent. The first impulse affecting the relay D is repeated to the relay E over the wire 20 through the contacts d' and d . The relay E becoming energized, closes the circuit of the relay F' by the following path: battery B, 21, e^3 , e^4 , 22, F' to ground. The operation of this relay places battery on the contact e' by the following path: battery B, 21, e^8 , e^9 , 28, f^{10} , f^9 , 13 to e' . The relay F' also places battery on the extension wire 13 which is common to all the locking contacts of the relays in the set W . Battery is now placed on the wire 18 through the contacts e and e' but the contact h' of the relay H' is open at this juncture and the relay W' is not affected. After the first impulse the relay E becoming deenergized closes the contacts e' and e^2 placing battery on the wire 19 through the contacts w' and w to the relay H' and ground. The relay H' thereupon becomes energized and locks itself through the contacts h^2 and h^3 leading to the locking wire 13. The contacts h and h' are also closed thus connecting the wire 18 to the relay W' through the contacts h^4 and h^5 of the relay H^2 . The second impulse, energizing the relay E , in turn closes the circuit of the relay W' by the path just traced. After the second impulse the contacts e' and e^2 being closed, the circuit of the relay H^2 is completed through the contacts w' and w^2 of the relay W' . The first impulse which comes in does not operate any of the selective relays W' , W^2 , etc., but 125 130

simply closes the circuit of the relay H' placing the set W', W², etc., in condition to be operated. The sending device at the subscriber's station in this case must be so adjusted as to always send one impulse more than the number wanted, or in the case where push buttons are used, the button will have to be depressed an extra time. The third impulse operating the relay E first 10 closes the circuit of the relay W² through the contacts h⁴ and h²⁰ of the relay H², and second, the relay H³ through the contacts w⁸ and w⁹ of the relay W². The fourth impulse operating the relay E closes the circuit 15 of the relays W³ and H⁴. When the relay W' was operated at the second impulse the circuit of the first tens relay T' was closed by the following path: battery B, 21, w³⁷, w³⁶, w²⁹, w³⁰, w²¹, w²², w¹³, w¹⁴, w⁶, w⁵, 23, T', 20 15, f⁴, f³ to ground. This relay T' does not remain locked as the common locking wire 16 is open in the relay F. At the third impulse the operation of the relay W² closes the circuit of the relay T² over the wire 24 and 25 at the same time opens the circuit of the relay T' by breaking the contacts w¹⁴ and w¹³. At the fourth impulse the relay W³ operating 30 closes the circuit of the relay T³ and at the same time opens the circuit of the relay T² by breaking the contacts w²² and w²¹. The relay T³ contains the contacts of the desired line and during the interval it takes the subscriber to set up the second digit, the circuit of the solenoid X' is opened at the contacts d² and d and the core dropping down 35 closes the contacts x² and x³ thereby placing a grounded impulse on wire 50. This impulse closes the circuit of the relay E' by way of d⁶ (Fig. 1), d⁵, 56, x³, x², 50 (into Fig. 2), E', f¹¹, f⁶, 12, 21, B and ground, which in turn closes the circuit of the relay F by way of B, 21, e⁸, 17, F and ground to battery. In the relay E' the opening 40 of the contacts e⁸ and e⁹ and e⁶ and e⁵ disconnects the relay F' and releases all of the relays in the set W. The operating of the relay F connects battery to the wire 16 which maintains the circuit of the relay T³ which is energized at this time. The relay 45 T³ is the only one of the set that can be affected by battery being placed on wire 16 as its locking circuit is connected to ground through the contacts 250 and 200, respectively. Ground is now removed from the common wire 15 of the tens relay by the 50 opening of the contacts f³ and f⁴ and ground is connected to the common wire 14 of the units relay. The relay set W is now again in position to be operated by the second set of impulses, the only difference being that the units relays are now controlled in place of the tens relays. The subscriber now sends in the proper set of impulses to select the second units relay T¹². The relays in the set 55 W are operated in the same manner as be-

fore and when the relay W² is selected the circuit of the relay T¹² is closed through the wire 24. The calling subscriber is now connected to the desired party through the trunk circuit and contacts of the tens and units relays. The relay Y, Fig. 1, now becomes energized in series with the interrupting machine through the contacts of the units relay by way of B, 63, d⁴, d³, 54, Y (through Fig. 2 into Fig. 3), through contacts t¹², to commutator and ground, and places generator current on the called line by way of the generator leads (Fig. 1), tip side of trunk, 7, through Fig. 2 into Fig. 3, contacts t¹², contacts t³, called line, back through the same contacts t³ and t¹² to the trunk wire 8, and so into Fig. 1 and back to generator. When the called party answers, the relay E² is energized cutting off the ringing relay Y. At the end of the conversation 80 the calling subscriber hanging up his receiver deenergizes the relays D and D', allowing the core of the solenoid X to drop down. After the core of the solenoid has dropped down, the contact springs x and x' are disconnected, removing battery from the wire 9, thereby releasing the relays F and F' which in turn release the relays in the set W which in turn disconnect the tens and units relays, thus restoring all the apparatus to its 85 normal condition.

Having thus described my invention, what I claim and desire to secure by Letters Patent is:

1. In a telephone exchange system, a plurality of line circuits, a group of relays containing contacts connected so as to form combinations adapted to directly interconnect the said line circuits, and means associated with the line circuits for sending a series of selective impulses of a predetermined total number to control the said relays, substantially as described.

2. In a telephone exchange system, a plurality of line circuits, a plurality of relays having contacts adapted to directly interconnect the said circuits, and means for selectively controlling the said relays through the line circuits by means of a predetermined total number of current impulses sent thereover, substantially as described.

3. In a telephone exchange system, a plurality of line circuits having substation and central station terminals, with impulse transmitters at the former, and switching sets at the latter composed exclusively of tens and units relays, and circuit connections whereby said impulse transmitters may act selectively and successively upon the tens and units relays of the relay sets through the line circuits, substantially as described.

4. In a telephone exchange system, a subscriber's station and a central station, and a line circuit interconnecting the same, automatic switching relays for connecting the

- line with other lines, a separate step by step number selecting device for said switching relays, and means at the subscriber's station for setting said step by step device through the line circuit so as to predetermine the connection to be made by the switching relays, substantially as described.
5. In an automatic telephone system, the combination of a line circuit having automatic switching apparatus at the central station for interconnecting it with other line circuits, a set of step by step number selecting relays for said switching apparatus, and means for selectively controlling said relays by current changes in the line circuit, substantially as described.
10. In an automatic telephone system, a plurality of line circuits, a plurality of relay connector sets for interconnecting the same, a plurality of step by step relay sets controlling the connector sets, and subscribers' impulse sending devices for actuating the controlling relays, substantially as described.
15. In an automatic telephone exchange system comprising metallic circuit lines, fast and slow relays for each line responsive to makes and breaks in the metallic circuit only, relay connectors for the lines, and step by step mechanism adapted to actuate said relay connectors and selectively controlled by the fast and slow relays, substantially as described.
20. In an automatic telephone system, a plurality of metallic circuit subscribers' lines, a device at each sub-station to make and break its metallic circuit, a relay at the central office responding to the makes and breaks, a plurality of selector relays controlled by said relay, and a plurality of connector relays controlled by the selector relays, substantially as described.
25. In an automatic telephone system, a plurality of subscribers' lines, relays having contacts included in and adapted to directly interconnect the lines, and subscribers' senders adapted to send a predetermined total number of impulses for controlling the relays, substantially as described.
10. In an automatic telephone system, a metallic circuit subscriber's line, a plurality of other lines, a set of relays having contacts included in said lines and adapted when properly energized to interconnect the same, a make and break device in the metallic circuit subscriber's line, and means responsive to makes and breaks in the line for controlling said relays, substantially as described.
5. In an automatic telephone system, the combination of a line circuit having automatic switching apparatus at the central station for interconnecting it with other line circuits, a set of step by step number selecting relays for said switching apparatus, and means for selectively controlling said relays by current changes in the line circuit, substantially as described.
10. In an automatic telephone system, a metallic circuit subscriber's line, means for connecting said line with other lines including a group of step-by step relays, and means at the subscriber's station for making and breaking the metallic circuit and thereby actuating said relays, substantially as described.
15. In an automatic telephone system, a metallic circuit, subscriber's line, a central station, automatic switching mechanism at said central station, said switching mechanism consisting of a series of relays, a pair of controlling relays having different time constants associated with said switching relays, and being themselves controlled by makes and breaks in the subscriber's line circuit.
20. In an automatic telephone system, subscribers' line circuits, impulse sending devices thereat, a quick acting relay at the central station for transmitting said impulses, a pair of controlling relays responsive to said impulses, one of said relays being a slow acting relay, and an automatic switch comprising a series of relays adapted to effect a talking connection between the subscribers' lines in response to the action of said controlling relays.
25. In an automatic telephone system, a plurality of subscribers' lines, relays having contacts included in and adapted to directly interconnect the lines, and subscribers' senders adapted to send a predetermined total number of impulses for controlling the relays, substantially as described.
30. In an automatic telephone system, a metallic circuit subscriber's line, a central station, automatic switching mechanism at said central station, said switching mechanism consisting of a series of relays, a pair of controlling relays having different time constants associated with said switching relays, and being themselves controlled by makes and breaks in the subscriber's line circuit.
35. In an automatic telephone system, subscribers' line circuits, impulse sending devices thereat, a quick acting relay at the central station for transmitting said impulses, a pair of controlling relays responsive to said impulses, one of said relays being a slow acting relay, and an automatic switch comprising a series of relays adapted to effect a talking connection between the subscribers' lines in response to the action of said controlling relays.
40. In an automatic telephone system, a metallic circuit subscriber's line, a central station, automatic switching mechanism at said central station, said switching mechanism consisting of a series of relays, a pair of controlling relays having different time constants associated with said switching relays, and being themselves controlled by makes and breaks in the subscriber's line circuit.
45. In an automatic telephone system, a metallic circuit subscriber's line, a central station, automatic switching mechanism at said central station, said switching mechanism consisting of a series of relays, a pair of controlling relays having different time constants associated with said switching relays, and being themselves controlled by makes and breaks in the subscriber's line circuit.

In testimony whereof I affix my signature in presence of two witnesses.
